United States Patent Office.

JAMES HOTCHKISS AND EZRA BUSS, OF SPRINGFIELD, OHIO.

Letters Patent No. 64,223, dated April 30, 1867.

IMPROVED DIE FOR BRICK AND TILE MACHINES.

The Schedule referred to in these Letters Patent and making part of the same.

TO ALL WHOM IT MAY CONCERN:

Be it known that we, JAMES HOTCHKISS and EZRA BUSS, of Springfield, in the county of Clark, and State of Ohio, have invented an Improved Die for Brick and Tile Machines; and we do hereby declare that the following is a full and exact description thereof, reference being had to the accompanying drawings, making part of this specification—

Figure 1 being an edge view of the improved die made for a brick machine.

Figure 2, a front outside view thereof.

Figure 3, a central vertical section of the same.

Figure 4, an inside view thereof.

Like letters designate corresponding parts in all of the figures.

The main feature of our invention consists in the use of friction-rollers located just outside of the mouth of the die, and projecting inward sufficiently to contract the rope or ribbon of clay, and receive the full pressure thereof for the purpose of diminishing the friction in the die and of giving a smooth and perfect surface to the clay. In connection with the rollers, we also contract or taper the inner surface of the die to, the outer edge or mouth thereof, its sides projecting along the surfaces of the rollers, so as to deliver the clay to the rollers near the middle or innermost projecting surfaces thereof. Also, in connection with the rollers, we employ scrapers located close to the surfaces of the said rollers, to clear them of any clay which may adhere to them.

Let A represent the die-plate, and B the aperture of the die, being of the proper size and shape to make a continuous rope or ribbon of clay, to be cut off into bricks or tiles of any shape to which our invention may be applicable. We use, or may use, a friction-roller for each face of the die. Thus, for bricks we use two rollers, C C, for the sides of the bricks, and two rollers, D D, for the ends. The inner surfaces, P P, of the die contract toward the outward edge or mouth, as shown in fig. 3, and deliver the rope of clay to the rollers nearly but not quite to the middle or innermost surfaces thereof, substantially as shown, so that the rollers project a little further inward, and receive the full pressure of the clay. The rollers revolve freely as the clay is spun out, and change sliding to rolling friction. In order to apply these rollers in the most successful and perfect manner to this purpose, certain peculiarities of construction and arrangement we find to be desirable, if not essential.

First. A capability of adjustment inward and outward and sidewise is desirable. This we conveniently effect by the employment of adjustable bearings, as G G for the journals *c c* of the rollers C C, and H H for the journals *d d* of the rollers D D. The flanges *g g* and *h h*, respectively, of these bearings, have slots or notches, *ff*, through which set-screws, *ll*, pass and fasten, as in the die-plate A. Any equivalent means of adjustment may be adopted.

Second. The edges, *s s*, of the rollers are mitred or bevelled, and their adjacent mitred surfaces are brought close together, substantially as shown. This allows the different rollers to be adjusted, to a considerable extent, either out and in, or sidewise, without injuring the perfection of the corners of the die, so that the corners of the bricks are sharply and accurately formed. The extent or proportion of the chamfer may be about as indicated in the drawings, or varied therefrom.

Third. The rollers are made slightly convex or bulging in the middle, substantially as shown, for the purpose of compensating for the swell of the clay as it emerges from the die, and also, if desired, of making the bricks slightly concave, so as to enable them to be laid more closely or with coarser mortar. The extent of the bulge may be only very slight, or varied to suit the purpose intended.

The scrapers I I are located outside of the rollers, being secured to the die-plate by screws, *n n*, passing through slots *m m* therein, or equivalent means, whereby also the positions of the scrapers may be adjusted. They have sharp edges which are brought close to the surfaces of the rollers, substantially as shown, so as to act properly to scrape off the adhering clay. Their edges are also curved concavely, to correspond with the convexly-curved surfaces of the rollers.

What we claim as our invention, and desire to secure by Letters Patent, is—

The employment of friction-rollers, either adjustable or not, applied to the dies of brick and tile machines, for the purposes herein specified.

We also claim the contraction of the die to the mouth thereof, in combination with friction-rollers on the die, substantially as and for the purpose herein set forth.

We also claim the mitred or bevelled edges of the rollers, for the purposes herein specified.

We also claim the convexly-curved or bulging form of the rollers, for the purpose herein set forth.

We also claim scrapers I I, in combination with the rollers, substantially as and for the purpose herein specified.

The above specification of our improved die for brick and tile machines signed by us in presence of two subscribing witnesses.

JAMES HOTCHKISS,
EZRA BUSS.
